(57) **CLAIM**

The ornamental design for a watch for health data monitoring, as shown and described.

DESCRIPTION

FIG. 1 is a front perspective view of a watch for health data monitoring, showing our design.

FIG. 2 is a bottom rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front perspective view thereof, showing the watch for health data monitoring in an alternate configuration.

The broken lines in the drawings illustrate portions of the watch for health data monitoring and form no part of the claimed design.

1 Claim, 9 Drawing Sheets
